[57] CLAIM

The ornamental design for a toaster, as shown and described.

DESCRIPTION

FIG. 1 is a top, front and right side perspective view of a toaster showing our new design;

FIG. 2 is a right side elevational view thereof;

FIG. 3 is a front elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The broken line showing of the toast holding rack in FIG. 6, as well as the broken line showing of the crumb tray in FIG. 7, is for illustrative purposes only and forms no part of the claimed design.
